UNITED STATES PATENT OFFICE.

WILLIAM ALBERT WELTON, OF LITTLE ROCK, ARKANSAS, ASSIGNOR OF ONE-THIRD
TO FREDERICK E. FARLEY AND ONE-THIRD TO CHARLES PHILIP WATERS, BOTH
OF LITTLE ROCK, ARKANSAS.

SIGNAL LANTERN.

Application filed August 7, 1922. Serial No. 580,171.

To all whom it may concern:

Be it known that I, WILLIAM ALBERT WELTON, a citizen of the United States, residing at Little Rock, in the county of 5 Pulaski and State of Arkansas, have invented certain new and useful Improvements in Signal Lanterns, of which the following is a specification, reference being had to the accompanying drawings.

- 10 This invention relates to lanterns such as carried by trainmen and others, and particularly to lanterns which are convertible from an ordinary lantern to a signal lantern or danger lantern by the provision of means whereby a red or other colored screen may be disposed around the burner of the lantern so that the lantern will display a red or other colored light when occasion requires.
- 15 One of the objects of this invention is to provide a lantern of this kind of a very simple construction, in which the body of the lantern is of ordinary form, and in which the screen lifting devices are mounted upon the bowl or base of the burner.
- 20 A further object is to provide a construction of this character wherein the colored glass screen is normally disposed between the oil font and the casing or base of the burner, and provide means upon the exterior 25 of this casing or base whereby the screen may be raised up around the burner of the lantern or depressed between the oil font and the base.

25 A still further object is to provide means whereby the screen may be locked in its raised position when it is desired to use the lantern with the screen for any considerable length of time.

Another object is to provide means whereby the base or casing of the oil font and screen may be detachably engaged and locked to the frame of the lantern.

A further object is to provide means whereby the font may be detachably locked in place within the casing or base but is rendered easily removable therefrom.

Other objects have to do with the provision of a lantern of this character which shall be very simple and, therefore, cheaply made.

My invention is illustrated in the accompanying drawings, wherein:

Figure 1 is a side elevation of a signal

lantern constructed in accordance with my invention;

Figure 2 is a top plan view of the base of the lantern partly broken away;

Figure 3 is a vertical sectional view through the base of the lantern;

Figure 4 is a fragmentary perspective view of the casing 20 and the parts coacting therewith;

Figure 5 is a fragmentary perspective view of the rim 12;

Figure 6 is a fragmentary perspective view of the upper portion of the casing 20 partly in section;

Figure 7 is a circumferential section through the rim 20;

Figure 8 is a perspective view of the slide- 70 able frame and the glass screen supported thereby, the screen and frame being separated.

Referring to these drawings, it will be seen that the frame of the lantern is of 75 ordinary form, comprising the base ring 10, the upright wires 11 which extend upward and inward from the base ring and are connected to a supporting band 12 and then extend upward and outward, as at 13, these 80 wires at their upper ends supporting a ring 14 upon which the hood 15 normally rests, this hood being held downward in engagement with the ring 14 by a spring clasp of any suitable construction. This hood is provided with the usual perforated cap 16 and the bail or handle 16^a pivotally engaged with eyes formed on the oppositely disposed uprights 13.

The band 12 is illustrated in Figure 5 as 90 formed of a sheet of metal approximately right angular in cross section, the sheet metal being perforated at intervals for the uprights 13 and being bent around these uprights. The downwardly extending portion 95 of the band has an opening 18 at one point, through which the wick raising shaft passes, and this band is also provided with a plurality of outwardly projecting pins or studs

19. Detachably engaged with the band 12 100 is the casing 20, cylindrical in form and closed at its bottom and perforated intermediate its top and bottom by the perforations 21 and flanged at its upper end. At its upper end the casing is flanged outward, as at 22, then extends upward, as at 105

23, and at its upper edge is outwardly extended and then downwardly extended, as at 24, so as to form an open bead. The flange 22 is formed at intervals with circumferentially extending slots 25, which slots open into vertical slots 26 formed in the casing and extending downward from this flange 22 to any suitable extent. The vertical portion 23 of the upper end of the casing is formed at one point with an opening 27 and at a plurality of points with the angular or bayonet slots 28, the vertical legs of these slots extending into the bead 24, as at 29. Attached to the exterior of the vertical wall 23 is a latch 30 which is somewhat resilient and is attached at one end to the wall, as by riveting, brazing or soldering, the opposite end of this latch being outwardly bent, as at 31, to form a handle and being notched to accommodate the bead 24, as at 32, and having inward of this notched portion an aperture 33. This latch is so arranged that the aperture 33 coincides with the longitudinally extending arm of one of the bayonet slots 28.

These bayonet slots 28, it may be remarked, are intended to receive the studs 19, while the opening 27 is designed to align with the opening 18 to permit the passage of the handle or shaft whereby the wick of the lamp is raised or lowered.

Sliding upon the outer face of the casing 20 is a ring 34 which has an outwardly projecting, somewhat fluted or corrugated flange 35 forming a handhold whereby the ring may be lowered or raised and given a slight rotation. Extending upward from the ring are the rods 36 which coincide with the slots 26, these rods being connected at their upper ends by a ring 37 which is interrupted at one point 38. The rods 36 are preferably, through not necessarily, T-shaped in cross section so that a portion of each rod will operate in the slot 26, while the lateral flanges will lie upon the outside of the casing 20. Each rod is also provided with an inwardly projecting stud 39 which form the supports for the colored glass screen 40. This screen at its upper end is formed with a bead 41 which rests upon the ring 37. The screen is also vertically slotted, as at 42, this slot coinciding with the interruption 38 in the ring 37.

While I have referred, as above, to this screen being of glass and while this screen preferably will be of glass, I do not wish to be limited to this, as the screen might be formed of celluloid or like more or less transparent colored material. Neither do I wish to be limited to the screen being of transparent or translucent material, as the screen might be of more or less opaque material and conceal the light of the lantern instead of making it appear as a colored light. This screen rests upon the lugs 39

and, therefore, as the screen supporting frame formed by the rings 34 and 37 and the rods 36 moves upward, the screen will be moved upward, and as it is moved downward the screen will be moved downward. 70

For the purpose of holding the screen supporting frame raised on the casing 20, the exterior of the casing 20 is formed with one or more short tongues 43 and the ring 34 is formed with one or more grooves 44 75 on its inside face which align with these lugs or tongues (see Figure 4). When the ring 34 has been moved upward above these lugs or tongues, however, the ring may be given a slight turn, permitted by the width of the slots 26, which will cause the lug or tongue to engage the bottom of the ring and hold it upward. A slight reverse turn will, of course, release the ring 34 from its engagement with the lugs or tongues 43 and 80 permit the depression of the screen carrier, holder or frame. 85

The oil cup is designated 45 and is provided with a plurality of studs 46 and with the usual burner 47 having a wick operated by the wick lifting shaft 48. The bottom of the casing 20 is formed with an annular flange 49 having T-shaped bayonet slots 50 with which the studs 46 are adapted to engage when the oil font is inserted in the casing and given a slight turn. Thus the oil font is locked in place. The usual glass shade 51 is held in place by the hood at its upper end and at its lower end rests upon the seat formed by the ring 12. 100

In the use of this device and under normal circumstances, the screen 40 is lowered into the casing 20 so that it is entirely enclosed within the casing and the lamp lens shows a white light and may be used for all the ordinary purposes of a white light lamp. When it is desired to use the screen, however, and thereby convert the lamp into a danger lamp or signal lamp by the use of a colored light, upward pressure is applied 105 to the ring 34, which carries the screen supporting frame or holder upward until the colored screen surrounds the burner of the lamp. When the screen has been fully raised, a slight rotation to the right is given 110 to the ring 34, which causes the tongues 43 to lock the screen held in its raised position. A slight rotation to the left unlocks the screen holder and permits the screen holder to be lowered again and the screen concealed. 120

The font 45, as above remarked, locks within the casing 20 and the casing 20 locks through the ring 12 by lifting the casing until the depending flange of the ring 12 is inserted between the ring 23 and the screen holder and then giving a slight turn to the casing. This causes the studs 19 to enter the bayonet slots 29 and 28 and when the casing is given a slight turn, one of these studs springs into the opening 33 of the latch 125 130

31 and the parts are locked in their position and cannot become unlocked unless this spring latch is retracted.

It will be seen that ordinarily the lantern 5 operates precisely like any ordinary lantern and is used in the same manner, but it is quickly convertible into a signal lantern whenever desired. Trainmen, flagmen and other operators on trains will use a red 10 screen for their signal lantern, car repair men will use a blue screen, and agents at flag stations will probably use a green screen. Obviously other colors may be used.

I claim:—

15. 1. In a lantern of the character described, a supporting frame having a hood and a handle, a globe supporting annulus disposed intermediate the top and bottom of the frame, a font holding casing having its upper end flanged to surround the annulus and formed at intervals with bayonet slots, the annulus having outwardly projecting pins engaging in said slots and the casing having a latch engaging one of said pins to hold 20 the casing from rotation, the lower end of the casing having an upwardly projecting circular wall inward of but concentric to the casing wall and formed with a bayonet slot, a font detachably mounted in the casing and having a burner, and a wick adjusting device, the font at its lower end having a pin engageable with the bayonet slots of said wall.
2. A lantern of the character described 25 comprising a frame and a globe supporting annulus carried by the frame, a cylindrical casing detachably engaged with said annulus and depending therefrom, an oil font detachably locked within said casing and 30 spaced from the inner face thereof and carrying a burner at its upper end, the cas-

ing being vertically slotted at a plurality of points, a vertically movable ring mounted upon the exterior of the casing and having vertical rods having portions projecting 45 through said slots having sliding engagement therewith, a screen normally disposed between the oil font and the casing, the rods having seats upon which said screen rests whereby as the ring is raised or lowered the 50 screen is raised or lowered, the screen being slotted for the passage of the wick raising shaft of the burner, and means for locking the ring in its raised position upon the casing. 55

3. In a lantern of the character described, a supporting frame having an annulus formed to provide a globe seat, the annulus having a depending flange formed with studs, a cylindrical casing having a flanged 60 portion at its upper end and formed with bayonet slots with which said studs are adapted to engage, the casing being vertically slotted, a screen carrier comprising a ring surrounding the exterior of the casing 65 and slidably mounted thereon, vertical rods operating in said vertical slots of the casing, the rods being connected by a ring at their upper ends, said ring being split at one point, a colored screen disposed within the 70 screen carrier and resting upon the upper ring, the screen being vertically slotted, an oil font detachably mounted within the casing and between the screen and having a burner at its upper end, a wick raising shaft 75 extending outward through the slot in the colored screen, and means for locking the screen carrier in a raised position with the screen surrounding the burner.

In testimony whereof I hereunto affix my 80 signature.

WILLIAM ALBERT WELTON.
